DESIGN FOR A LANDING GEAR

Carl G. Seyferth, Muskegon, Mich.

Application June 26, 1937, Serial No. 70,079

Term of patent 3½ years

To all whom it may concern:

Be it known that I, Carl G. Seyferth, a citizen of the United States, residing at Muskegon, in the county of Muskegon and State of Michigan, have invented a new, original, and ornamental Design for a Landing Gear, of which the following is a specification, reference being had to the accompanying drawing, forming a part thereof.

In the drawing:

Figure 1 is a rear elevational view of a land-

ing gear showing the same in lowered position, and

Fig. 2 is a side elevational view of the landing gear shown in Fig. 1.

I claim:

The ornamental design for a landing gear, as shown.

CARL G. SEYFERTH.
